UNITED STATES PATENT OFFICE.

EDGAR M. HAWKINS, OF ROCHESTER, NEW YORK, ASSIGNOR TO M. D. KNOWLTON COMPANY, OF ROCHESTER, NEW YORK, A CORPORATION OF NEW YORK.

SAFETY OPERATING MECHANISM.

1,296,798.

Specification of Letters Patent. Patented Mar. 11, 1919.

Application filed September 18, 1914. Serial No. 862,480.

To all whom it may concern:

Be it known that I, EDGAR M. HAWKINS, citizen of the United States, and resident of Rochester, in the county of Monroe and State of New York, have invented certain new and useful Improvements in Safety Operating Mechanism, of which the following is a specification.

The present invention relates to that type of safety devices for presses, punching machines, box staying machines and the like, intended to transmit power from the actuating means to the work-performing element only when the same is in close proximity to the work to be operated upon. At all other times, the work-performing element will yield if it meets with an obstruction, such as the operator's hand, and, therefore, no harm will be done.

20 The object of this invention is to provide a safety device or safety operating mechanism of this kind having the improvements hereinafter set forth.

The invention is illustrated in the accompanying drawings, which show the safety operating mechanism applied to a box-staying machine, but it will be obvious that it may be used on other types of machines as well.

30 In the drawings:—

Figure 1 is a front elevation of a portion of a box staying machine, certain parts being broken away to show the safety operating mechanism;

35 Fig. 2 is an enlarged view of the safety operating mechanism showing the parts in the position which they assume just prior to the engagement of the work by the work-performing element;—and

40 Fig. 3 is a vertical section taken on the line 3—3 of Fig. 2.

The box staying machine illustrated in the drawings is of the usual construction, and comprises a movable die A and a stationary die or anvil B. The movable die A is carried by a reciprocating slide C provided with a rearwardly projecting pin D. This pin is connected to and driven by the actuating shaft E, which, in the present instance, is provided with a crank pin F. The crank pin F is connected with the pin D by a link or pitman construction, which is constructed in the novel manner hereinafter described,

to constitute the safety device or safety operating mechanism hereinbefore referred to. 55

The safety operating mechanism or safety link comprises two power transmitting elements, one of which is indicated at 1, and is journaled on the crank pin F, and the other is shown at 2, and is pivotally connected 60 with the pin D. A bushing 3 may be interposed between the pin F and the part 1, and a similar bushing 4 interposed between the pin D and the part 2.

The depending power transmitting element 1 has a bifurcated lower extremity forming an elongated opening 5, in which the pin D engages and in which it is freely slidable. The parts 1 and 2 are connected by means of a pin 6 secured in the part 2 70 and engaging in an opening 7 in the part 1, preferably having the shape shown in Fig. 2. An enlarged head 8 on the pin 6 overlies the face of the part 1, and serves to hold the parts 1 and 2 together. 75

The depending power transmitting element 1 is provided with a shoulder 9, which is adapted to engage with a corresponding shoulder 10 formed on the power transmitting element 2. The parts are yieldingly 80 held in the position shown in Fig. 2, in which the shoulders 9 and 10 are in engaging relation, by means of a spring 11, having one or more convolutions wound around the hub of part 2, and having one of its extremities secured to the part 1 and the other extremity secured to the part 2. A suitable stop 12 may be provided for limiting the movement of the part 2. 85

An extension of the pin F is formed into 90 a cam 13, and is so shaped that just after the movable die A leaves the work on the up stroke of the safety link, the part 2 will be shifted to the position shown in Fig. 1, in which the shoulders 9 and 10 are out of 95 engaging relation. The cam 13 holds the part 2 in this position during the up and down stroke of the link until the movable die A, or work-performing element, is about $\frac{1}{4}$ of an inch from the work to be operated upon. At this time, the cam assumes the position shown in Fig. 2, and permits the spring 11 to shift the part 2 to the position shown in Fig. 2. The shoulders 9 and 10 are then in engaging relation, and pressure 100 is transmitted from the crank pin F through 105

the parts 1 and 2 to the pin D, the same as if a solid link were provided between the pins F and D.

If the work-performing element, which, in the present instance, is the movable die A, encounters any obstacle during its downward movement, such as the operator's hand, the parts 1 and 2 will yield or move relative to each other, since the pin D and part 2 will be held stationary by the obstacle, and as the shoulders 9 and 10 are not in engaging relation, the part 1 and crank pin F will continue their downward movement without applying any pressure to the work-performing element. The openings 7 and 5 permit this relative movement between the parts 1 and 2, and allow the part 1 to make its downward stroke without affecting the part 2 which is being held stationary by the obstacle under the work-performing element. When an obstacle is so met with, and the parts move relative to each other, as just described, the upper extremity of the part 2 will be thrown to one side of the cam 13, and the cam in descending will move downward relative to the upper end of the part 2, in an obvious manner.

Obviously, any obstruction over $\frac{1}{2}$ of an inch in thickness will cause the parts to collapse or move relative to each other, as above described, since the shoulders 9 and 10 are not in engaging relation at any time, until the work-performing element is $\frac{1}{2}$ of an inch from the work to be operated upon. When the shoulders 9 and 10 are not in engaging relation, no pressure will be applied to the obstacle under the work-performing element, and, therefore, the operator's hand, if accidentally caught between the dies, will be uninjured.

What I claim is:—

1. In a machine of the kind described, the combination with the actuating means and a work-performing element, of a normally inoperative power-transmitting element pivotally associated with the work-performing element, and means associated with and actuated by the actuating means automatically operable just prior to the engagement of the work by the work-performing element to permit said power-transmitting element to shift to its operative position.

2. In a machine of the kind described, the combination with the actuating means and a work-performing element, of a normally inoperative power-transmitting element pivotally associated with the work-performing element, and a cam associated with the actuating means and operable just prior to the engagement of the work by the work-performing element to permit said power-transmitting element to shift to its operative position.

3. In a machine of the kind described, the combination with the work-performing

element and its actuating means, of two normally inoperative power-transmitting elements, one being associated with the work-performing element and the other with the actuating means, and a cam associated with the actuating means to permit that element which is associated with the work-performing element to shift to its operative position just prior to the engagement of the work by the work-performing element, and thereby establish a positive connection between the two power-transmitting elements.

4. In a machine of the kind described, the combination with the actuating eccentric and the work-performing element, of two power-transmitting elements one being mounted on the eccentric and the other associated with the work-performing element, and positively-acting controlling means normally maintaining said power transmitting elements in inoperative relation and operable to permit of their assuming operative relation to each other just prior to the engagement of the work by the work-performing element.

5. In a machine of the kind described, the combination with the actuating eccentric and the work-performing element, of two power-transmitting elements one being mounted on the eccentric and the other associated with the work-performing element, said power-transmitting elements provided with shoulders adapted to engage to transmit power from the actuating means to the work-performing element, and positively-acting controlling means normally maintaining said power-transmitting elements in inoperative relation with their shoulders out of engagement with each other and operable to permit of their assuming operative relation with their shoulders in engagement just prior to the engagement of the work by the work-performing element.

6. In a machine of the kind described, the combination with the actuating means, and a work-performing element, of a normally inoperative power-transmitting element pivotally associated with the work-performing element, means tending to yieldingly hold said power-transmitting element in its operative position, and a cam associated with the actuating means to control the movement of said power-transmitting element and operable just prior to the engagement of the work by the work-performing element to permit the power-transmitting element to be shifted by said means to its operative position.

7. In a machine having a work-performing element and an actuating eccentric, a safety-link connecting the same and comprising two parts for transmitting power to the work-performing element, one of said parts being connected to the actuating eccentric and the other to the work-perform-

- ing element, controlling means carried by said eccentric for normally maintaining one of said parts in inoperative relation to the other and operable to release the same just 5 prior to the engagement of the work by the work-performing element, and means automatically operable to shift said part to operative position relative to the other following its release by said controlling means.
- 10 8. Safety operating mechanism for the work performing element of machines of the kind described, including a safety link comprising two relatively slidable portions normally held in an inoperative position for 15 transmitting power, and automatic means for shifting the position of one of the parts to permit said parts to contact and render the same effective for transmitting power, just prior to the engagement of the work by 20 the work-performing element.
9. Safety operating mechanism for the work-performing element of machines of the kind described, including a safety link comprising two relatively slidable portions, 25 a cam for normally holding one of the portions in an inoperative position for receiving power from the other portion, and a spring for shifting the position of the cam-held portion when released by the cam to permit 30 the two portions to contact and thereby render the same effective for transmitting power, said cam adapted to release the portion held by the same just prior to the engagement of the work by the work-performing 35 element.
10. Safety operating mechanism for the work-performing element of machines of the kind described, including a safety link comprising two relatively slidable portions 40 provided with shoulders adapted to directly engage each other when said portions are in their operative position, and means to control the relative sliding movements of said portions so that said shoulders will automatically engage at a predetermined point 45 during the operative movement of the link and prior to the engagement of the work by the work-performing element.
11. In a machine of the kind described, the 50 combination with the actuating eccentric pin and a pin associated with the work-performing element, of a normally inoperative power-transmitting member pivotally associated with one of said pins and extending 55 to the other, and a cam associated with the actuating eccentric pin normally operative to maintain said power transmitting element in an inoperative position, but automatically operable just prior to the engagement 60 of the work by the work-performing element to permit said power-transmitting member to shift to its operative position.
12. In a machine of the kind described, the 65 combination with the actuating eccentric and the work-performing element, of two normally inoperative power-transmitting elements, one being mounted on the eccentric and the other associated with the work-performing element, and means automatically operable just prior to the engagement of 70 the work by the work-performing element to shift one of said elements to establish a positive connection between the two.
13. In a machine of the kind described, the combination with the actuating eccentric 75 and the work-performing element, of two normally inoperative power-transmitting elements, one being mounted on the eccentric and the other associated with the work-performing element, said power-transmitting 80 elements provided with shoulders adapted to engage to transmit power from the actuating means to the work-performing element, and automatically operable means to shift one of said elements just before the 85 work-performing element reaches the work to cause said shoulders to engage and thereby establish a positive connection between the two.
14. In a machine having a work-performing 90 element and an actuating eccentric, a safety-link connecting the same, and comprising two parts normally inoperative for transmitting power to the work-performing element, one of said parts being connected to 95 the actuating eccentric and the other to the work-performing element, and automatically operable means to shift one of said parts, to establish a positive connection between the two parts just prior to the engagement 100 of the work by the work-performing element to render said part operative for transmitting power to the work-performing element.
15. In a machine of the kind described, 105 the combination with the actuating eccentric and the work performing element, of two power transmitting elements, one being mounted on the eccentric and the other associated with the work-performing element, 110 positively acting controlling means normally maintaining said power transmitting elements in inoperative relation and operable to permit of their assuming operative relation just prior to the engagement of the 115 work by the work performing element, and means for automatically shifting one of said elements into engagement with the other.
16. In a safety device having a work-engaging element and driving means for reciprocating the same, means for automatically rendering said driving means inoperative when the path of the element to the work is obstructed, comprising a link and 120 pawl connected to the element and giving movement by the reciprocating means, said link being a one-piece member engaging at its opposite ends with the work-engaging element and the driving means respectively, 125 130

and means to automatically interlock said link and pawl when the path of the element to the work is free.

17. In a machine having a work engaging element and an anvil, means for reciprocating said element to exert pressure upon the anvil comprising an interlocking link and pawl, a cam to automatically and positively unlock the pawl from the link to render the work engaging element inoperative, and means to automatically lock the pawl and link just prior to the engagement of the work by the work performing element.

18. In combination with a driving means, a reciprocating work engaging element, means comprising a full link and pawl to connect said driving means and element, said link being a one-piece member engaging at its opposite ends with the driving means and work-engaging element respectively, means to automatically lock said link and pawl to exert a working action upon the work-engaging element at a predetermined

point, and means to automatically unlock the link and pawl at a predetermined point to prevent working action of the element.

19. In a machine having a reciprocating work engaging element and an anvil, a driving means, means comprising a pawl and full link to connect the driving means and reciprocating work engaging element, said link being a one-piece member engaging at its opposite ends with the driving means and work-engaging element respectively, and means to automatically operate the pawl to lock same with the link to exert a working action upon the element, and automatic means to unlock the pawl from the link.

Signed at Rochester, in the county of Monroe and State of New York, this 12th day of Sept. A. D., 1914.

EDGAR M. HAWKINS.
